UNITED STATES PATENT OFFICE.

JOHN T. SKILLINS, OF WESTBROOK, MAINE, ASSIGNOR TO DANA COTTON HARVESTER COMPANY, A CORPORATION OF MAINE.

VACUUM NOZZLE FOR COTTON HARVESTERS.

Application filed May 28, 1920. Serial No. 384,965.

To all whom it may concern:

Be it known that I, JOHN T. SKILLINS, a citizen of the United States, residing at Westbrook, in the county of Cumberland 5 and State of Maine, have invented certain new and useful Improvements in Vacuum Nozzles for Cotton Harvesters, of which the following is a specification.

My invention relates to vacuum nozzles 10 for pneumatic cotton harvesters.

These nozzles are attached to the end of the suction hose which latter are connected with the exhaust fan on the machine. The nozzle to which the present invention relates 15 consists essentially of a cylindrical casing having therein a rotatable tubular picking nozzle mounted on ball bearings within the casing.

The picking tube is provided with propeller blades which cause its rapid revolution at the same time the suction draws the cotton onto the picking tube and thence 20 through the suction hose.

It is found by experience in the cotton field that it is very difficult to keep the ball 25 bearings free from dirt and grit and as a result the balls are subjected to rapid wear.

The cause of the rapid wearing away of the ball bearings is the fact that there is a slight vacuum in and around the bearing 30 caused by the rapid flow of air through the picking tube and through the casing and this vacuum tends to draw into the ball bearing any dirt which may leak in between the casing and the picking tube. Thus if 35 the ball bearing is ever so well shut in and protected the fine dirt and grit will find its way in and cause the rapid wear of the parts. It is impossible to protect the ball bearing from dirt by any ordinary system 40 of packing since the picking tube must be allowed to rotate freely and the slightest friction between the casing and picking tube will tend to destroy the efficiency of the nozzle.

The object of my invention is to construct a vacuum nozzle of such form that there will be a slight vacuum in and around the bearing but so arranged that any foreign substances will be drawn out from and away from the bearing instead of being drawn into it and thus doing away with the necessity of a tight packing.

I accomplish this object as shown by ad- 55 mitting to the upper or outer end of the

picking tube a lateral current of air which passes adjacent to the ball bearing in such a direction that the latter is subjected to a slight vacuum and all dirt is expelled and diverted from the bearings.

As a result of this construction the nozzle may be used in the dirtiest place and with the dirtiest cotton and the bearing be always clean and free from dirt. The life 65 of the nozzle will thus be greatly extended and its practicability for actual work in the field assured.

I have illustrated my invention in the accompanying drawing in which is shown a vacuum nozzle constructed in accordance 70 with one embodiment of my invention.

In the drawing:—

Fig. 1 is a longitudinal section drawn full size,

Fig. 2 is a section the same as a portion 75 of Fig. 1 but greatly enlarged,

Fig. 3 is a plan of the picking sleeve and,

Fig. 4 is an elevation of the same,

Referring to the drawing, 1 represents the body of the casing which is cylindrical 80 and enlarged at the upper end. The lower end 2 is reduced so that it fits inside the suction hose (not shown) through which a powerful draft of air is drawn, the same passing through the nozzle.

The nozzle is here represented for convenience and referred to as in an upright position, but it will be understood that in use it is liable to take any position.

To the upper end of the body 1 is connected by a screw threaded joint, the casing sleeve 3 which has an outward extending flange 4 at its upper end.

To the top of the flange 4 is bolted the flat cap 5 having a central opening with an 95 inwardly inclined conical surface forming the outer opening to the nozzle.

Within the casing just described is the rotatable picking tube made up of the lower member 6 and the upper member 7 connected together by the propeller blades 8 as shown and described in my application filed Nov. 29, 1918, Serial No. 264,584.

The air enters the openings in the sleeve 3 and passing down through the blades 8 cause the picking tube 6-7 to rotate. In the upper end of the picking tube 7 I have fitted a short picking sleeve 9, the upper end of which is formed of an outward projecting annular flange 10 and an inwardly pro-

jecting conical flange 11 with picking fingers 12 disposed horizontally at the upper surface of the picking sleeve. The two upper ball bearing cones 13 and 14 are disposed just below the flange 10, the inner cone 13 being secured to the upper end of the picking tube 7 and the opposite cone 14 being secured to the inner surface of the casing sleeve 3 with the ball 15 between them. Openings 16 are formed in the upper end of the picking sleeve 9 and immediately below the flange 10. A narrow space is left between the lower surface of the cap 5 and the upper surface of the flange 10. A space is also left between the outer edge of the flange 10 and the inner surface of the casing sleeve 3.

A space is also left between the lower surface of the flange 10 and the upper surface 20 of the ball bearing 13—14.

As here shown an inward projection 17 extends from the inner surface of the sleeve 3 and forms the bearing for the cone 14.

To exclude any dust coming from below 25 the bearing and from the external air passing to the blades I insert a ring 18 below the ball bearing and fitting closely as here shown to the interior surface of the picking sleeve 3.

30 The inner edge of the sleeve 18 fits the outer surface of the picking tube with a somewhat loose fit which will allow the picking tube to rotate freely.

The ball bearing 19 is constructed substantially in the same way as the upper ball bearing at the lower end of the picking tube 6, the bearing being interposed between the picking tube and casing. This bearing is protected from dust by a pair of rings 20 40 occupying a position between the lower end of the tube and the bearing 19.

The rings 20 act as guards or protectors against dust and dirt coming from an eddy which tends to form in the air just below 45 and outside of the lower picking tube 9.

The protective feature of my device operates as follows:—

One current of air enters through openings in the sleeve 3 passing downward 50 through the blades 8, enters the tube 6 and passing thence out of the nozzle and into the hose.

Another air current enters the upper end of the picking tube sleeve passing downward 55 through the contracted conical opening formed by the conical flange 11 and thence downward to the picking tube.

A small auxiliary air current, leaving the main current at the mouth of the opening, 60 passes in between the lower surface of the cap 5 and the upper surface of the flange 10, thence downward around the outer edge of the flange 10, inward through the space

between the lower surface of the flange 10 and the ball bearing and passes thence 65 through the opening 16 into the interior of the picking tube 3 beneath the conical flange 11.

This air current which is indicated by arrows in Fig. 2 passes over the opening between the opposing conical surfaces of the cones 13 and 14 and tend to create a slight vacuum in the ball space and to divert any grit or dirt which might otherwise lodge in the ball bearing carrying the same into the 75 interior of the nozzle or the picking tube where it is harmless.

As a result of this construction, the ball bearing is always kept clean and bright, there is no tendency to fill up with dirt and 80 grit so that the balls and their raceway will run a very long time without any perceptible wear, a very important consideration when the rotatable picking tube must run with the least possible friction in order to do its 85 work.

I claim:—

1. In a vacuum nozzle for pneumatic cotton picking machines, the combination of a casing, a rotatable picking tube therein 90 through which air and cotton are drawn, bearing means between the casing and the rotatable picking tube and means providing an auxiliary current of air communicating with said bearing means for withdrawing 95 dust and air from the same and producing a slight vacuum therein.

2. In a vacuum nozzle for pneumatic cotton picking machines, the combination of a casing, a rotatable picking tube therein 100 through which air and cotton are drawn, a ball bearing between the casing and the rotatable picking tube, openings being formed adjacent to said ball bearing and communicating with the interior thereof whereby a 105 portion of the incoming air is drawn through said openings and acts to partially exhaust the interior of said ball bearing and remove foreign matter therefrom.

3. In a vacuum nozzle for pneumatic cotton picking machines, the combination of a casing, a rotatable picking tube therein, 110 through which air and cotton are drawn, co-acting ball races on said picking tube and said casing, balls running therein, a flange 115 on said picking tube immediately below said ball races and making a nearly tight joint between said picking tube and said casing, an air passage being formed adjacent to said ball races whereby the main air supply will 120 act to partially exhaust the space between said races.

In testimony whereof I have affixed my signature,

JOHN T. SKILLINS.
